(57) CLAIM

The ornamental design for a 4-drawer dresser, as shown and described.

DESCRIPTION

FIG. 1 is a front, right and top perspective view of a 4-drawer dresser showing our new design;

FIG. 2 is a front view thereof;

FIG. 3 is a rear view thereof;

FIG. 4 is a left side view thereof, a right side view being a mirror image of the left side view;

FIG. 5 is a top view thereof;

FIG. 6 is a bottom view thereof;

FIG. 7 is a rear, bottom, and left perspective view thereof; and,

FIG. 8 is a partially enlarged view showing the circled portion 8 in FIG. 7.

The broken lines depict portions of the 4-Drawer Dresser that form no part of the claimed design.

The dot-dash broken lines in FIGS. 7 and 8 form no part of the claimed design.
